Emery executrix of said Frederick L. Emery,
deceased

Application March 5, 1929, Serial No. 344,246

36 Claims. (Cl. 93—7).

This invention relates to packeting machines, commonly so called, or machines for forming, filling and closing containers or packets made of paper or other flexible material, particularly where it is desired to effectively seal and protect the contents from the air whether or not the container is to be subsequently enclosed in a carton. Such packets may contain cereals, spices and other dry materials, particularly when it is desired to sell them in measured quantities in dust and air proof containers.

The invention aims to provide a novel and improved machine having, among others, the novel features herein shown and described.

In the drawings of one embodiment of our invention selected for illustration and description herein,

Fig. 1 is a front elevation;

Fig. 2, a diagrammatic plan, partly in section, of the driving mechanism for the several packet forming and closing elements taken on the line 2—2, Fig. 1;

Fig. 3, a vertical section on the line 3—3, Fig. 1, of the packet forming plunger housing on an enlarged scale, showing also its operating connections;

Fig. 3A, a cross section of the plunger on an enlarged scale on the line 3A—3A, Fig. 3;

Fig. 4, a rear elevation of that portion of the plunger housing indicated by the arrows 4—4, Fig. 3, showing its operating mechanism,

Fig. 5, a vertical section on an enlarged scale on the line 5—5, Fig. 1, through the lower part of the plunger housing and adjacent cooperating parts showing, also in section, the paper feeding mechanism;

Fig. 6, a front elevation of the side wall mechanism of the packet fashioning means and the packet cooling means partly in section;

Fig. 7, a vertical section in part on the line 7—7, Fig. 1, and in part diagrammatic, showing the packet detecting mechanism;

Fig. 8, a vertical section on an enlarged scale of a portion of Fig. 5, showing the elements used in effecting the first step of the packet forming operation, including the paper folding elements for forming the minor or narrow packet faces;

Fig. 9, a front elevation of parts shown in Fig. 8, showing the paper sheet folded to form the major side walls and in position to be initially folded to form the minor packet walls;

Figs. 10 and 11 show, respectively, further steps in the folding of the sides and bottom of the packet;

Fig. 12, a front view of some of the parts shown in Fig. 9 including the partially formed packet;

Fig. 13, a detail front elevation of the bottom minor flap folding members and showing the packet entering the carrier;

Fig. 14, a rear elevation of the minor top flap

indenting or first folding step members in dotted lines and, in full lines, the operating connections therefor;

Fig. 15, a side elevation and partial section on the line 15—15, Fig. 1, of the same parts and of the parts for performing the second folding step;

Fig. 16 is a front diagrammatic view of the first top folding step mechanism and mode of operation;

Fig. 17 illustrates the method of performing the second top folding step and elements for effecting the same;

Figs. 18 and 19 respectively, a front, and a side view on the line 19—19, Fig. 1, of the third, top folding elements;

Fig. 20, a side partly sectional view of the same elements during the effecting of the third folding step;

Fig. 21 illustrating a similar view of the method of effecting the fourth, top folding step;

Figs. 22 and 23, front and side elevations respectively, the latter partly in section on lines 23, 23, Fig. 1, of the fifth top folding step instrumentalities;

Fig. 24, a similar view of the fifth top folding step mechanism and illustrating its method of operation;

Fig. 25, a side elevation on line 25—25, Fig. 1, of the sixth step or top fold positioning means and the ejectors;

Fig. 26, a diagrammatic view of the ejecting operation and showing the top sealing plate holding the sealed top fold in position to enter the conveyor;

Fig. 27, a view partly in elevation and partly in vertical section on line 27—27, Fig. 1, showing the hopper and operative connections for charging the packets;

Fig. 28, a horizontal partial section on the line 28—28 of Fig. 27, through the hopper;

Fig. 29, a cross-section through the charging device looking down on the line 29—29 of Fig. 27;

Fig. 30, a diagrammatic view showing substantially on the line 30—30, Fig. 27, the charging means control, part of which is on the bottom face of the movable hopper and part on the upper face of the chute plate;

Fig. 31, a partial vertical section and partial elevation of the material charge leveller; and

Fig. 32, a partial vertical section on the line 32—32, Fig. 30.

Our novel packeting mechanism comprises, Figs. 1, 2, a base or bed plate 1 which may be supported on legs 2, and the bed, Figs. 1, 2, 5, 55 may have depending front and rear members or aprons 3, 4. The bed, Figs. 5, 7, is grooved or channeled at 5 to receive an endless conveyor 6. This conveyor is provided, Fig. 5, with a carrier 7 partly offset from the center line of the con-

5

60

veyor, which carrier receives the packet forming material, as paraffin paper, from the packet forming elements, which will be described presently. Beside the carrier, Figs. 1, 5, is a 5 guide 8 on brackets 9 on the base to assist the carrier in maintaining the packet in proper position as it is presented to the successive elements to be described, which perform upon it various functions usually at designated points, conveniently termed stations, which will be described in order.

For this purpose, Fig. 2, the conveyor is given an intermittent forward motion by means of a beveled pinion 10, on the main cam shaft 11 in 15 mesh with a similar gear 12 on the shaft 13 carrying a Geneva driving and locking arm 14 which, with a Geneva spider 15 on the shaft 16 provides a Geneva gear, as it is commonly called, which imparts intermittent motion to a carrier sprocket 20 17 over which runs the endless conveyor 6, Fig. 1.

On the back of the machine it is provided, Fig. 2, with a main driving pulley 19 on a shaft 20 extended laterally of the bed 1, and this shaft carries at its inner end a beveled pinion 21 in 25 mesh with a similar gear 22 on a second lateral or cross shaft 23.

This shaft 23 carries a beveled pinion 24 on its inner end in mesh with a beveled gear 25 on the main cam shaft 11, and the shaft 23 also carries 30 at its opposite end a beveled pinion 26 in mesh with a second beveled gear 27 on what we term a front cam shaft 28.

On one, and Fig. 1, the right hand end of the bed is a tall housing 29 for the packet forming 35 plunger 30, also Figs. 3, 5, the housing having several plunger bearings, Fig. 3, as 31. Power for operating this plunger, Fig. 2, is provided by a sprocket 32 on the shaft 20 which carries a chain 33, Fig. 1, running, Fig. 3, to a similar 40 sprocket 34 on a shaft 35, in a bearing 36 on top of the bed 1, and bearing 37, Fig. 3, on the rear of the housing 29, this bearing and also bearing 38 above it being held in position by clamps 39 engaging both sides of the housing 29. Shaft 35 carries a sprocket 40, see Figs. 3, 4, which, 45 in turn, carries a chain 41 running to a second sprocket 42 mounted in the bearing 38.

This chain, Fig. 4, has engagement with the plunger 30 by means of a lug 43 on the chain, 50 which lug carries a roll 44 in a slot 45 in a plate 46 clamped to the plunger, the roll traveling from the left hand end of the slot to the opposite end as the lug 43 travels upwardly and over the upper sprocket 42 and then downwardly, and in the 55 reverse direction as the lug passes downwardly, beneath sprocket 40, and then upwardly on the opposite side.

The first function, Fig. 5, performed by the machine between stations one and two is the supplying of paper of proper width in the form of a strip 50, from a roll 51 supported in a bracket 52 on the rear of the bed 1. This strip 50 passes beneath a valley roll 522 journaled in a slotted post 523 on the bracket 52 and then between feed 60 rolls 53 rotated by any convenient means, not shown here, and thence between the supporting roll 54 and a cooperating rotary cutter 55 operated as will presently be described. The roll 522 acts to prevent the formation of wrinkles in the 65 paper as it is fed upward, and the roll drops in the slotted post as the roll of paper diminishes in size.

By the cutter 55, Fig. 5, the paper strip is severed at the proper time to produce a piece 56 of proper size to make one packet and therefrom

it passes over the table 57 beneath pressure rolls 58 in a frame 59. This frame has a curved end pivoted at 60 to the housing 29, and about which the rolls 58 and frame 59 swing to retain the strip 56 flat in its proper position and condition to be fed by the roll 60 beneath guides 61, 62 to the position shown in Fig. 5 for action thereon by the plunger 30.

The roll 54 and cutter 55 are geared to be rotated by a chain 65 from a sprocket 66, Figs. 2, 15, on the shaft 11. From a sprocket 69 on the same shaft, Figs. 2, 5, there runs a chain 75 to a sprocket 76 on the shaft 77, over which runs an endless paper carrier 78 to the roll 79 for carrying the severed paper strip beneath the rolls 58 to the plunger. Obviously any desired detail mechanism for operating the paper feeding and severing rolls may be used for that purpose.

The strip of paper 56 from which the packet is to be made having been positioned as shown in Fig. 5, the plunger 30, Fig. 8, operated as already described, descends at station two, and forces the paper strip 56, dotted lines, down between front and rear packet-wall-forming members 82, 83, Fig. 5, secured to brackets 84 and 25 85 extended between and secured to opposite sides of the housing 29 on the bed 1, thus forming the major side walls of the packet.

For forming the minor walls of the pocket, Figs. 8, 9, 10, we have provided novel and movable wall forming plates 86, 87 adjacent the fixed member 82 and a similar movable plate 88 adjacent the member 83. These plates 86, 87, 30 88 are carried on opposite ends of the stud shafts 89, Figs. 5, 8, 9, 10, in the brackets 84, 85, the 35 lower shafts being provided with dogs 92, 93 projecting into the path of the plunger 30. The rear or outer ends of the dogs 92 adjacent the member 82 are connected by links 94 with arms 95 on the upper shaft 89 carrying plates 86. 40

In the edge of the table 57, Fig. 8, is a roll 951 on each side of the plunger 30, each roll mounted in a slot 952 and yieldingly retained in position by a spring 953 for the purpose of facilitating the uniform movement of the paper beneath the 45 plunger 30.

When the U-shaped strip of paper backed by the plunger in its downward travel reaches a point slightly below its position as shown in Fig. 8, the paper enclosed plunger engages the dogs 50 92, turns them downwardly and their rear ends 93, turns them downwardly and their rear ends upwardly, throwing the plates 86, 87 inwardly and downwardly and causing them to bend the projecting edges of the paper strips 56, Fig. 9, inwardly, Fig. 10, about the plunger. 55

Immediately after one edge of the bent strip of paper has been folded inwardly by the plates 86, 87, Fig. 8, the paper and its plunger engage the opposite dogs 93, and depress them, causing the plates 88 to fold the edge of the opposite side of the strip of paper inwardly, Fig. 11, thus forming the minor packet walls and leaving the triangular minor wall folds or tabs 90.

At their lower ends, Fig. 11, the brackets 84, 85 carry front and rear bars 844 and 845 respectively, between which are suspended hollow bars 846, 847, each containing a heating unit 99, the four members 844, 845, 846, 847 forming a rectangular opening and tab sealing aperture 96, with curved upper edges 97 adjacent the 70 minor packet walls, which edges, Figs. 9, 12, 13, are heated by any suitable means, as electricity, through wires 98, connecting with wires to be described leading from the top of the plunger 30, Fig. 3, to the heating elements 99, dotted 75

lines, above referred to, within the bars 846, 847. As the tabs 90, Fig. 12, and overlapped minor packet walls move downwardly past these rounded edges 97, the tabs and overlapped edges 5 are warmed sufficiently by the plunger 30, heated by the elements 301 through the wires 302, Figs. 3, 3A, and the heated bars 846, 847, to cause the paraffin or substitute therefor to melt, and the overlapped packet edges are pressed together 10 between the plunger and walls 844, 845, 846, 847 and the tabs are pressed closely against the minor side walls of the packet, and as the parts cool, they adhere firmly to each other.

15 The elements 846, 847, Fig. 6, are yieldingly held in carton contacting position by springs 99^a seated against the ends of the blocks 846, 847, and the plates 95^b on the ends of elements 844, 845, the ends of the elements 846, 847 protruding through and sliding in the slots 99^c in the 20 members 844, 845.

25 As the packet A is forced through the tab and fold sealing aperture 96, it is positioned by the plunger 30 in the carrier 7 immediately beneath it, Figs. 13, 16, with its top projecting above the carrier, where it is received, Fig. 16, upon a vertically sliding bottom member 100, with a lining of wood 100^a, the carrier having minor wall members 101 and major walls 102, Fig. 17, preferably all of oiled wood, so that the waxed 30 paper packet will not adhere to them. The bottom 100 is prevented from leaving the carrier 7, Figs. 16, 17 by the top flanges 103 and bottom plates 103^a.

35 In its travel from the opening 96 to the carrier 7, the packet is guided, Figs. 9, 12, 13, by a fixed guide plate 104 and an opposite guide plate 105 movable on a shaft 106 and adapted to swing longitudinally of the machine in the direction 40 the carrier moves to permit the packet A to be advanced by the carrier. This swinging guide plate feature is shown clearly in Fig. 6, wherein the shaft 106 is shown provided with a gear 107 meshing with a segmental gear 108 on a stud shaft 109 in a bracket 110 over the bed 1.

45 On the rear end of this shaft there is also fixed, Fig. 5, one end of the long arm 111 of a lever 112, also dotted lines, Fig. 5, the opposite end of which arm carries a rod 112^a, on the lower end of which is secured a roll 113, dotted lines, Fig. 6, which travels in a suitable cam groove, in a cam disk 114 on the shaft 11. The action of the roll in the cam is so timed that when the packet is about to be fed forward to station three, or to the left, Fig. 6, the rod 112^a 50 is raised with the lever arm 111 and segmental gear 108, rotating the gear 107 to the right and swinging the plate 105 to the left leaving the path clear for the upwardly projecting top of the packet, Fig. 6, to move to the left.

60 At this same point, station three, we have provided novel means to assist the quick cooling of the packet which was heated to effect the sealing operation of the overlapped side edges and triangular tabs. This means, Fig. 6, comprises a pipe 116 leading from a convenient source of cool air, if desired, but not shown, which, by a conventional blower, also not shown, provides a stream of air to be thrown by pipes 117, as four in number, into the four corners of 65 the open top of the packet A.

70 This cooling operation, Fig. 6, is controlled by a slide valve 118 in a seat 119 supported from the base 1, the valve having ports 120 adapted to register with the ends of the pipes 117. This 75 valve is controlled by a link 121 connecting it

with the short arm 122 of the lever 112, connected in turn by the long arm 111 and rod 112^a with the roll 113 in the cam 114, already referred to, Figs. 2, 6, thus opening the valve 118 to supply air to the packet while it is at rest. 5

The side packet fold and triangular tabs having been sealed, then prior to the upward withdrawal of the plunger 30 from within the packet, and prior to the movement of the carrier and packet to station four, the air, Fig. 16, is exhausted from the space beneath the packet A by a small passage 123 through the bottom lining 100^a of the carrier and passage 124 through the bottom 100 and beneath the packet, to offset any tendency of the packet to follow the plunger upward; the object being furthered by the action of the stripping boards 125^a, 125^b, Fig. 5, on the brackets 84, 85 adjacent the plunger 30, which catch the upper edge of the packet and act to prevent it from moving upward. 10 15 20

For this purpose, Fig. 5, there is provided below the carrier a plunger 126 carrying at its upper end a resilient cup 127, the plunger having therein a passage 128 adapted to register in proper position with the end of a pipe 129 in a block 130 on the base 1, the pipe leading to a vacuum creating device, not shown. The plunger head is also fluted, as at 303 on the sides and bottom, Fig. 3A, which permits air to pass down into the packet and thus act to prevent the formation of a vacuum within it. The plunger is preferably 30 of aluminum with hard metal wear plates 304 on the sides at the points where they get the most wear.

This plunger, Fig. 5, is actuated by a lever 131, 35 on a bracket 132 on the bed 1, one arm 133 of the lever being pivoted to the plunger while the opposite arm 134 carries a roll 135 which travels in a cam path 136 in a cam 137 on the shaft 11, see also Fig. 2. By the above described means, the 40 air is exhausted from beneath the packet A in the carrier before the plunger is withdrawn, as already pointed out.

The plunger having been withdrawn, the packet is advanced by the carrier to station four where 45 a novel packet-detecting device is utilized preparatory to the charging or filling operation, to make sure that the packet is in proper condition to receive the material. In Fig. 7, this device is illustrated as comprising an arm 138 pivoted to 50 a bracket 139 on the bed 1, and connected by a rod 140 with a cam 141, see also Fig. 2, on the shaft 11, the rod carrying a roll 142 in a cam path 143 by which up and down rocking motion is imparted to the arm. 55

The forward end of the arm overhangs the carrier 7 and carries at its end two stud shafts 144, 344, on each of which is a gear 145 in mesh with the other. On one end, Figs. 1, 7, of shaft 344 is an arm 146, dotted lines, which, in the 60 position shown, rests upon the upper end of a bracket 147 on the bed 1, the arm being suitably adjusted by a set screw 148 for such contact. The gears 145 are normally rotated toward each other by a spring 149 connecting posts 349 on the 65 gears, and when the gears are so rotated, their limit of movement is fixed by the contact of an arm 350 on the shaft 144 with a stop 351 on the arm 138, adjustment being provided by the screw 352. 70

Depending from the shafts 344, 144, Fig. 7, are arms 353, 354, each of which has a laterally extended passage 355, 356 therethrough and registering with each other. The passage in the arm 353 is the larger and is adapted to receive 75

a plunger 357 in the opposite passage normally pressed toward it by a spring 358 in the arm 354.

On the rear end of plunger 357 is a contact 359 connected by a wire 360 with a source of electric current, not shown. This contact will, when the plunger 356 is extended into the passage 355, engage a cooperating contact 361 on the arm 138 and also in circuit with the contact 359.

10 Normally, just prior to the movement of the carrier to station four, as shown in Fig. 7, the arm 138 will be in its upper position and the arms 353, 354 separated by action of the spring 149, carrying the arm 146 downward and the arm 350 upward against the stop 351.

When the packet arrives beneath the arms 353, 354, the roll 142 causes the arm 138 to swing downwardly and the contact of the stop 148 on the arm 146 against the top of the bracket 147 causes the gears to swing the arms 353, 354 toward each other and they will engage opposite sides of the packet as shown in Fig. 7.

This packet, if in proper position, will prevent the plunger 357 from entering the passage 355 to bring the contacts 359 and 361 together, and the arms will again be separated in due time by action of the roll 142 in the cam 141, and the operation of the machine continues normally.

If, through mistake, the packet has not been properly fashioned and positioned in the carrier, when it arrives beneath the arms 353, 354, the plunger 357 will not be prevented by it from entering the passage 355, contact 359 will engage contact 361, the circuit will be closed and, by any suitable means to be later described, the hopper discharging means will be locked so that it will not operate to charge the packet.

It having been determined, however, Fig. 6, that the packet is in proper condition to receive its material, it is next passed beneath a hopper 398 with discharging means or filling mechanism, Fig. 1, of any suitable and preferred type, at station five, to be described presently, where it is filled.

45 The packet having been filled, its upper end may now be sealed and it is advanced to station six where the first two steps are performed, and for this purpose, Figs. 14 to 16, we have conceived the following novel mechanism. The carrier brings the packet first beneath two vertically rocking end top-flap indenting or forming members 150, 151, Figs. 1, 14, 15, 16, depending in the path of the packet, on rocker shafts 152, 153, carried by a bracket 154 on the bed 1. 50 These rocker shafts, Fig. 14, carry gears 155, 156 respectively, in mesh with similar gears 157, 158 on shafts 159, 160 all carried by the bracket 154.

Desired rocking motion, Fig. 14, is imparted 60 to these members by means of a segment 164 on a shaft 165 carrying also an arm 166 on the bracket 154, and connected by a rod 167, Figs. 1, 2, 15, with a roll, not shown, traveling in a cam path, not shown, on the disk 172. Thus the members 150, 151, rock back and forth in the path of the packet and at the proper time engage opposite minor sides, Figs. 14, 16, of the top of the packet and indent or fold inwardly a V-shaped area 175, leaving the two major sides 70 176, 177 upstanding, somewhat narrowed at the top, as shown in Fig. 16.

To bring these top flaps together side by side and properly fold them, Figs. 15, 17, there is provided novel means comprising as the first step 75 in that proceeding heated interlocking, block-

like angular fold forming members 178, 179 with wires 180, 181 running to them from any source of electric current to melt or soften the wax or other suitable material on the packet paper, the members carried, Fig. 15, by arms 182, 183 on shafts 184, 185 above the packet path. These shafts carry interlocked gears 186, 187, the shaft 184 carrying also an arm 188 to which is pivoted a link 189 with a hollow boss 190 which receives the end of a rod 195 carrying about its upper end a helical spring 196 seated at one end against a collar 197 on the rod, and against the shoulder 198 on the boss 190 on the rod 195 at its opposite end. The rod 195 is locked in the boss 190 against inward movement, by a collar 199 on the rod.

The rod 195 carries at its lower end a roll, not shown, which travels in a cam path, not shown, in the disk 199, on the front cam shaft 22, Figs. 1, 2. The interlocking, Fig. 17, at the proper time through the action of the cam roll, of the two members 178, 179 against the outer faces of the two flaps 176, 177 gives the tops of the two flaps a substantially right angle fold.

This fold, Figs. 17, 18, 20, is next given at station seven, a downward turn, by the action of two downwardly folding members, Figs. 18, 19, 20.

The block or anvil 205 is carried by the long arm 207 of a bell crank lever pivoted at 208 to a bracket 209 on the base 1, the short arm 210 carrying a hollow boss or sleeve 212 on which seats one end of a spring 213 on the rod 214, the opposite end being seated against the collar 215 on the rod which is adjustably secured therein, and prevented from inward movement by means of a collar 216 on the rod. The rod carries at its opposite end a roll, not shown, in a cam path, not shown, in a disk 218, Figs. 1, 2, on the front cam shaft 28.

The beveled fold bending presser plate or hammer 206 is on a short arm 223 of a lever pivoted at 224 on the bracket 209, the long arm 225 being movably connected to a rod 226 having a one way yielding connection therewith as in the case of arm 210 and rod 214, the rod 226 carrying a roll, not shown, in a cam path, not shown, in a disk 227 on the shaft 11, Fig. 1.

By action of the roll and cam at the proper time the sharp nosed hammer 206, Fig. 20, is caused to press the folds 176, 177 firmly against the block 205 while the member is heated by wires 228, 229, and impart a downward bend to the partially right-angled turned upper edges of the folds.

For continuing this downward folding action, Fig. 19, the shaft 208 also carries a segment 230 on the arm 231, the segment being in mesh with an intermediate gear 232, which, in turn, meshes with a gear 233, both on the arm 207 previously referred to. The gear 233, in turn, engages a pinion 234 on a short shaft 235 on the block 205, the shaft 235 carrying also a short crimping member 236. The segment 230 is actuated through the arm 231 by a rod 238 similarly secured to the arm 231 as in the case of the rod 214 and arm 210, the rod carrying a roll, not shown, in a cam path, not shown, in the cam 239 on shaft 28, Figs. 1, 2.

By the elements described, after the members 205, 206 have closed upon the folds, Fig. 20, and given the fold the downward turn while heated, member 206 is withdrawn, Fig. 21, and the crimping plate 236 is, by the action of the rod 238 and the gears and segment described, Fig. 21, while heated caused to crimp the folds and to

bend them downwardly and still more closely together by the curved end of member 236 pressing them into a depression 205^a in the crimping end of the member 205.

8 To further effect the final downward folding and sealing of the flaps 176, 177, and to square up the top of the packet, they are next acted upon, Fig. 24, at station eight by the following members.

10 On the front side of the base 1, there is positioned an outwardly curved bracket 244, Figs. 22, 23, 24, in which is pivoted at 245 a lever, one arm 246 of which has, on its end, a laterally extended crimped flap pressing and bending jaw

15 247 substantially equal in length to the adjacent side of the packet top fold. This arm, Figs. 22, 23, also has pivoted to it at 248 a lever 249, having on one end a cooperating crimped flap pressing and bending jaw 250 with suitable elements,

20 not shown, and electric wires 251 for heating it. The other end of the lever carries a roll 252 which travels outwardly on an inclined rail 253 of the bracket 254 beneath the shield 253^a on said bracket and presses the members 247, 250 toward each other on opposite sides of the packet top and which rail 253A is cut away somewhat to permit downward swinging action of the jaw 250.

25 The opposite end of the lever 246 is adjustably connected like lever 238, Fig. 19, with a rod 255 which, in turn, carries a roll, not shown, in a cam path, not shown, in the disk 256, Fig. 2, by means of which rocking motion of the lever 246 is obtained.

When the packet arrives at station eight, the 30 jaws 247, 250 are open as at Fig. 23, and the crimped flaps, as in Fig. 21, are normally positioned between them. Thereafter through the described action of the lever 246 and the travel of the roll 252, the jaws are closed against the crimped flaps, as in Fig. 24, thus acting to draw 35 downwardly the upstanding closed packet top, squaring the top of the packet, and the paraffin of the paper is warmed by the heat from the jaw 250 sufficiently to cause the flaps to adhere under pressure of the jaws 247, 250, see Fig. 24,

40 which, when the roll 252 returns down the rail 253, subsequently reopen permitting the packet to be advanced to the ejecting position. This action of the jaws 247, 250 also acts to throw the upper end of the folded top laterally to the right of the center of the packet, and to thus leave the downturned packet top fold tucked somewhat beneath the laterally positioned top of the fold and helps to lock the end of the downturned 45 fold beneath the overhanging top and reduces the danger of its flying open.

To complete the sealing of the flaps by laying them down upon the top of the packet, as in Figs. 25, 26, additional means are provided, effective at station nine, which follow the action of the vertical ejector, in removing the packet from the carrier and positioning it in front of the horizontal ejector.

The bottom 100 of the carrier, Figs. 16, 17, 20, 50 21, 24, is acted upon, Fig. 25, at the proper time by a vertically operative ejector 257 slidable in a track 258 on the front of the bed 1. This ejector 257, Fig. 25, has pivotally connected to it a link 260 which, in turn, has pivotal connection with a link 261, in turn pivoted to an arm 262, Figs. 1, 2, 25, and cooperating with the cam disk 263 on the front cam shaft 28. By this means the ejector 257 is given a vertically reciprocating motion, and so timed, Fig. 25, that the packet is 55 ejected vertically at the proper time to a position

on a level with the upper run of the conveyor belt 265, Fig. 25, and immediately in front of the horizontal ejector 266 slidable, Fig. 25, in a bracket 267.

The shank of the ejector 266, Fig. 25, has pivoted to it a link 268 which is also movably connected with a long lever arm 269, whose short arm 270 carries a roll 271, traveling in a cam path 272 in a disk 273 on the shaft 11, see also Fig. 2. This cam arrangement is also so timed 10 that the ejector 266 is actuated at the proper time to force the carton delivered by the ejector 257, forwardly between the belts 265, 274 for delivery.

Immediately after the packet has been ejected 15 upwardly by the member 257, however, and during the ejecting operation of the horizontal ejector 266, there is a final sealing or fold tucking step effected by a novel mechanism for that purpose. The ejector 266 carries pivoted on its forward upwardly extended end 279, a fold tucking and heating plate 280 on the end of the curved arm 282 and connected by wires 281 with a source of electricity, not shown, which arm carries, on its opposite end, a roll 283 which travels on a rail 25 284 on the bracket 284^a. This arm is normally held down by a helical spring 285 secured to the member 266. When the ejector is in its retracted position, Fig. 25, the roll 283 is so positioned that the tucker 280 is elevated.

When, however, the ejector moves forward, Fig. 26, the roll 283 rides upon the upwardly inclined end of track 284 and the tucking plate 280 is turned downwardly and fed forwardly, Fig. 26, to a position just below the crimped folded 35 flaps 176, 177, and between them and the top of the packet. Then sufficient heat is applied through the wires 281 to warm the paraffin, and when the ejector 266 thrusts the packet between the belts 265, 274, Fig. 25, the warmed flaps 176, 40 177 are pressed down firmly upon the packet top, secured and cooled as the packet moves along in the conveyor.

While the container as described herein has been termed a "packet", it should be understood 45 that our invention as claimed and described is not to be limited thereby to containers that are not required by the nature of the intended contents thereof or by the strength of the material of which they are made, to be enclosed in other 50 containers, or cartons, for further protection.

Obviously sometimes it is desirable for protection of the container or contents to protect either or both by incorporating the container as a liner, in a second container, which may be done readily with the container already described; and in such case the container, even if termed something different, as a liner, is identically the same article but intended to be used for different materials, and as such is comprehended within the 60 description and terms of the claims covering our invention herein.

Referring again to the packet-detecting mechanism described heretofore, and illustrated in Fig. 7, and with particular respect to the material-charge control mechanism operated thereby, the wire 360 leads to a relay switch 365, shown herein diagrammatically only and which may be of any conventional construction, and herein as comprising a coil, the opposite end of which is 65 connected by wire 367 to the battery 368 or any suitable source of current, grounded through the wire 369 upon the bracket 147. This circuit is of low voltage, as 24, to avoid any danger to the operator from a short circuit in the machine. 75

The switch 365, Fig. 7, also comprises an armature 370 in the form of a contact or circuit closing member, which, when the coil is energized, is caused to engage the contact 371 from which a line 372 leads to a second source of current, as a commercial circuit of higher voltage, as 110, and also the contact 373, from which leads a wire 374 to one post of a solenoid 375, a line 376 leading from the opposite post to the ground. The core 377 of the solenoid, when actuated by the energizing of the solenoid, operates by suitable connection, not shown, the charge control mechanism which will now be described.

The charging device as a whole, Fig. 27, comprises a bracket 378 secured as by nuts and bolts, not shown, to the bed 1 of the machine. This bracket has a laterally extended arm 382 overhanging the base 1 and in the arm is journaled a hopper carrying shaft 383 connected with the upright shaft 384 extending through the base 1 and having on its end the worm gear 385 meshing with the worm 386, see also Fig. 2, on the shaft 11.

The shaft 383 is carried, Fig. 27, in a hub-shaped bearing 388 in the center of a dish-shaped plate 389 fast on the arm 382 and which carries a depending chute 390 to guide the material-charge to the packet A below in the carrier 7. On the upper end of the bearing 388 is any suitable ball bearing 391 supporting a collar 392 fast on the shaft 383 and carrying a disk 393, see also Fig. 29, with several outlets 395 about its outer edge. In each of these outlets is a collar 396 which receives in its upper end the lower end of a sleeve 397 in the bottom of a hopper 398 held fast by a nut 399 and a flange 400 on the upper end of the screw 401 threaded into the shaft 383 and rotating therewith. The hopper 398 may be adjusted as to height relative to plate 393 by adjustment of screw 401 relative to shaft 383 and locking it if desired by lock nut 383.

Within the hopper 398 there is a reservoir 402 carried by an arm 403 on a bracket 404 in turn adjustable on the bracket 378, by means of nuts 405, on opposite sides of the rib 406 of that bracket. The reservoir 402 has a slide 407 near its lower end to control the flow of material therefrom to the hopper.

The bracket 404, Figs. 27, 28, also carries a sprocket 408 on a shaft 409, a chain 410 running from the sprocket down to the sprocket 411 thence around driving sprocket 412 on shaft 11 to sprocket 413 and back up to sprocket 408, sprockets 411 and 413 being carried on the lower end of a bracket 414 adjustable on base 1.

On the opposite end of the shaft 409, Figs. 27, 28, is a bevel gear 415 in mesh with a gear 416 on the lower end of a shaft 417 carrying on its upper end a sprocket 418. About the sprocket runs a chain 419 to a sprocket 420 on a shaft 421 carried by the laterally extended arm 422 on the bracket 404.

The shaft 421 extends down into the hopper 398 directly over the path of travel of the sleeves 397 and carries on its lower end a novel material-charge leveller 422^a. This leveller, Fig. 31, is in the form of a hollow cylinder having spiral grooves 423 running upwardly about its outer wall, and is positioned to nearly touch the bottom of the hopper. The material flows from the reservoir to the hopper 398 and fills the several sleeves 397, which, with the disks to be described, may be said to form cups, with material as each cup arrives at the lowest point in the rotation 75 of the hopper.

As each cup in its upward travel, Fig. 28, arrives beneath the leveller 422^a, it rotates thereover and levels the charge to the bottom of the reservoir so that all charges are of uniform size. As the leveller rotates, the surplus charge is caused to travel up on the outside thereof in the grooves 423 and part of it at least is thrown laterally beyond and below the baffle plate 424 and gravitates downwardly to the cups at the lower portion of the hopper, and we thus avoid cutting and otherwise breaking and scratching the grains or pieces of the material, which happens if the leveller simply rotates amongst them in one place.

To prevent any material from escaping the action of the leveller and moving upwardly toward the discharge chute, we provide, Fig. 28, the curved baffle plate 424 already referred to, which accomplishes the purpose.

The disks 426, Figs. 27, 28, 29, 30, 32, which form the bottoms of the cups already referred to as they close the ends of the sleeves 397, and the operation of which control the delivery or non-delivery of a charge of material, are carried upon the long arms 427, Fig. 32, of levers pivoted at 428 on the plate 393. The short arms 429 of these levers each carry a roll 430 on its lower face, which roll, Figs. 29, 30, 27, 32, normally travels against the upturned circumferential edge of the plate 389 on the arm 382, and when so traveling, Fig. 29, the long arm 427, with its disk 426, will be positioned directly beneath the end of one of the collars 396 in the plate 393 and with it and the sleeve 397 form above it a cup to hold the charge of material.

In order, however, to swing this disk away from the cup and thereby dump the charge into the packet as each cup arrives over a packet, the edge of the plate 389, Figs. 29, 30, is cut away at the proper point and provided with a narrow plate 431 to form a cam surface, and the roll 430 is caused by the cam-shaped plate and a switch member 433 pivoted on a shaft 434 on the disk 393 to move inwardly and thus swing its disk outwardly, Fig. 29, away from and to open the end of the sleeve or bottom of the cup over the chute 390 and dump its charge into the packet. The cam plate 431 will thereafter, Fig. 29, cause the roll to travel outwardly and swing the disk back into normal position to again form a cup by closing the end of its sleeve.

This closing is so positioned and timed that it happens late enough to allow the cup to entirely dump its contents, but early enough to be fully closed again before the material begins to flow again into the cup from the hopper, thereby preventing any spilling or jamming of the material.

In order, however, to effect the purpose of the detector heretofore referred to, Fig. 7, and automatically control the action of the disk in respect to dumping its charge, the plate 389, Figs. 29, 30, has pivoted to its upper face near the circumferential edge and opposite the low point of the cam plate 431 a switch 433 with a cam-shaped inner and outer face which is normally open, Fig. 29, so that the roll 430 will pass inside it. The stud shaft 434 on which the switch is mounted, however, Figs. 30, 32, carries fast on its lower end an arm 435, the end of which is connected pivotally to the core 377 of the solenoid 375.

Referring now to the description of the detecting mechanism as shown in Fig. 7, page 21, when the carrier 7 arrives at the charging point in its travel, with no packet or a distorted packet and

the plunger 356 therefore, when it moves, encounters no packet, and enters the slot 355, the contact 359 engages the contact 360, closes the circuit through the relay switch 365 and solenoid 375, located beneath the plate 399, the core 377 of the latter is withdrawn, with the solenoid arm 435, throwing the long arm of the switch 433 inwardly, Fig. 30, and seating the outer end of the arm 435 in the depression 436 in a second arm 437 on the plate 393 acted upon by a spring 438 seated against it and an arm 439 fast on a stud 440 upon which also the arm 437 is pivoted.

This action, Fig. 30, also closes the cam path of the roll 430, causing the latter to continue its travel about the outer edge of the plate 389 without swinging the disk 426 on its lever arm away from the collar 396 and dumping the charge of material. As soon as the carrier leaves the position shown in Fig. 7, the circuit through the relay switch and solenoid is broken and the core 377 and arm 435 are returned to normal position, Fig. 30, by the roll 430 traveling over the cam surface of the short arm of the switch 433, the lever 427 being prevented from swinging inwardly at this time by the stud 441 in the plate 393. The outer end of the arm 435 is forced back and seated in the depression 442 in the arm 437 and is held in that position by the action of the spring 438.

30 In this manner should a carton in imperfect condition for any reason, be encountered, the annoyance and waste of dumping a charge therein will be avoided and in the case of some materials, these are very important advantages.

35 Our invention is not limited to the precise embodiment thereof described and illustrated but is more particularly pointed out in the following claims.

We claim:

40 1. In a packeting machine comprising an endless conveyor and packet forming material feeding and cutting means; packet forming means including packet wall shaping members, a plunger for forcing the material therebetween, and movable wall fashioning plates; heating means to cause the material edges to adhere; means respectively for exhausting the air beneath the plunger, cooling the heated material, detecting the presence of a packet; packet filling means, flap folding means and sealing means, and packet ejecting means.

45 2. In a packeting machine comprising an endless conveyor, packet forming material feeding means including a frame with a plurality of rolls to maintain the material in position and in contact with the feeding rolls; packet forming means comprising wall shaping members and a plunger for forcing the material between the walls and to form the bottom; movable wall fashioning plates positioned to bend the material about the plunger to form additional walls; heating means to cause the material edges to adhere; means respectively for exhausting the air beneath the plunger, cooling the heated material, detecting the presence of a packet; packet filling means, flap folding means and sealing means and packet ejecting means.

50 3. In a packeting machine comprising an endless conveyor, packet forming material feeding and cutting means, and packet wall forming means; means to heat the material handling members to cause the material walls to adhere; means respectively for exhausting the air beneath the plunger, cooling the heated material, detecting the presence of a packet; packet filling means,

flap folding means and sealing means and packet ejecting means.

5 4. In a packeting machine comprising an endless conveyor, packet forming material feeding and cutting means, packet wall shaping members including a plunger and material heating means; packet anchoring means including an apertured packet-carrier member and means for withdrawing air from said member beneath the packet to prevent it from following the withdrawing 10 plunger; and means respectively for cooling the heated material, detecting the presence of a packet; packet filling means, flap folding means and sealing means and packet ejecting means.

15 5. In a packeting machine comprising an endless conveyor, packet forming material feeding and cutting means, packet wall shaping members, packet anchoring means; means including air supplying means and pipes leading to the walls of the packet for cooling the heated adhering packet 20 material while at rest; means for detecting the presence of a packet; packet filling means, flap folding means and sealing means and packet ejecting means.

25 6. In a packeting machine comprising an endless conveyor, packet forming material feeding and cutting means, packet wall shaping members, material heating means, packet anchoring means, packet filling means, and means, including a plurality of arms with a cooperating plunger and 30 socket, and electric contacts to control operation of the filling mechanism mounted to engage opposite sides of one packet wall if in proper position, and thus prevent movement of the plunger into the socket, and engagement of the contacts; 35 and means respectively for cooling the heated material, top flap folding means and sealing means and packet ejecting means.

7. In a packeting machine comprising a conveyor, material feeding and cutting means, packet 40 wall shaping members, material heating means, packet anchoring means, air supplying means; packet detecting means, and means including a hopper and rotating shutters thereon to fill the packet and means respectively to fold the top 45 flaps and eject the packet.

8. In a packeting machine comprising a conveyor, packet material feeding and cutting means, packet forming means including wall shaping members, movable wall fashioning members; 50 material heating means, packet anchoring means, direct air supplying means, packet detecting means, packet filling means, top flap folding and sealing means including a plurality of flap engaging members acting progressively to fold the upwardly extended flaps downwardly, lay them upon the packet top and seal them thereto, and packet ejecting means.

55 9. In a packeting machine comprising a conveyor, packet forming material feeding and cutting means; packet forming means including wall shaping members, movable wall fashioning members; material heating means; packet anchoring means; direct air applying means, packet detecting means, packet filling means, flap folding and sealing means including a plurality of differently fashioned flap engaging members with means for heating them acting progressively to fold the upwardly extended flaps downwardly, lay them upon the packet top and seal them thereto; and upwardly acting ejecting means to position the packet before a conveyor and longitudinally acting ejecting means for forcing the packet into the conveyor.

10. In a packeting machine, wall shaping members with resiliently mounted paper carrying members adjacent thereto and a plunger for forcing the material therebetween, and movable wall fashioning members for bending the material about the plunger and actuated thereby to complete the side walls.
11. In a packeting machine of the class described, an endless conveyor with a packet carrier thereon having a bottom member with an aperture therethrough and means for exhausting air therefrom and to anchor the packet therein.
12. In a packeting machine, wall shaping members and a plunger for forcing material therebetween, and laterally movable wall fashioning members actuable by the plunger as it is forced between the shaping members for bending the material about the plunger to complete the side walls.
13. In a packeting machine of the class described, an endless conveyor with a packet carrier thereon having a bottom member with an aperture therethrough, means for exhausting air therefrom and to anchor the packet therein and packet stripping means for removing the packet from the plunger.
14. In a packeting machine, wall shaping members and a plunger for forcing the material therebetween, and movable wall fashioning members actuable by the packet material as it moves between the shaping members for bending and overlapping the material about the plunger lengthwise of the packet, and forming triangular folds at the bottom; and a heated die through which the formed packet is forced to turn the folds back against the packet side walls and seal them thereto.
15. In a packeting machine, wall shaping members and a plunger for forcing the material therebetween, and movable wall fashioning members actuable by the packet material as it moves between the shaping members for bending and overlapping the material about the plunger lengthwise of the packet and forming triangular folds at the bottom, and a heated die through which the formed packet is forced to turn the folds back against the packet side walls and seal them thereto; and a hinged guide for guiding the packet into the carrier, and means to swing said guide from the packet path to permit advancing of the packet.
16. In a packeting machine, means for closing the top of a packet comprising heated interlocking members engaging opposite packet walls and imparting an angular fold thereto, and operating means therefor including levers overhanging the packet path, one lever carrying an anvil and a crimping member, a second lever carrying a hammer, and cooperating operative means causing the hammer and anvil to act upon the upright portion of the packet top flap and thereafter causing the hammer, anvil and crimping members to act first upon the bent portion of the packet top flaps and subsequently upon the upright and bent portions to position the base thereof.
17. In a packeting machine, means for closing the top of the packet comprising a heated block, a heated tapered hammer and means to cause them to engage opposite packet folds and impart a crimped fold thereto, acting first upon the upright portion of the packet top flap, thereafter upon the bent portion of the packet top flap, and a lever carrying a pair of jaws, a roll thereon, and a lower and upper rail therefor, and operating means therefor providing an angularly bent and base positioned closed top fold.
18. In a packeting machine including a conveyor, means to close the top of the packet comprising a heated hammer, block and a heated horizontal crimp making member and means to cause them to engage opposite packet folds and impart a horizontal crimp thereto substantially midway thereof, including levers carrying said hammer, anvil and crimping member in the path of the packet, operating means therefor, and a heated folded packet top tucker, a packet ejector having an arm thereon, a roll thereon and a rail therefor, acting to tuck the lower portion of the folded packet top beneath the upper portion to facilitate its engagement with packet conveying means.
19. In a packeting machine, means to close the packet top comprising a heated block, and a cooperating member and means to cause them to engage opposite packet folds and impart a partially turned under fold thereto, and means to square the packet top.
20. In a packeting machine, means to close the packet top comprising a heated plate and means for inserting it beneath the partially downwardly turned fold thereof, to heat and seal the fold and the packet top.
21. In a packeting machine, means to eject from a carrier and means to eject from the machine to a parallel belt conveyor a packet with a turned-under heated fold whereby the conveyor belts assist in sealing the packet top, and means simultaneously to heat seal and tuck a flat fold on the packet.
22. In a packeting machine having a carrier with a sliding bottom, means to eject from the carrier and means thereafter to eject from the machine a packet and simultaneously to heat seal and tuck a flat fold on the packet.
23. In a packeting machine, the combination with means for forming and sealing the packet, of detecting means including an electrical circuit, comprising a pair of movable arms constructed to engage respectively opposite faces of the packet if in proper position, a fixed contact member and a second contact member on one of the movable arms constructed to engage the first contact to indicate the presence of a mis-formed packet or the absence of a packet.
24. In a packeting machine, the combination with means for forming and sealing the packet, of detecting means including an electrical circuit, a plurality of arms with contact members thereon constructed to swing respectively clockwise and counterclockwise into the path of a packet at a predetermined point to determine the presence of the complete packet and engage same if there and charging mechanism operably controlled by a contact member.
25. In a packeting machine, the combination with means for forming and sealing the packet, of detecting means including an electric circuit, comprising a plurality of arms with contact members thereon constructed to move into the packet path at a predetermined time to determine the presence of a complete packet and close a circuit through the arm if packet is not present, and charging mechanism; and a solenoid in the circuit for controlling the same, operated by the contact members.
26. In a packeting machine, the combination with means for forming and sealing the packet, of detecting means including a plurality of packet engaging members constructed and ar-

ranged to move in parallel curved paths into the path of the packet at a predetermined time and then in oppositely directed curved paths to determine the presence of a complete packet, and engage it at the meeting point of their paths of travel with the path of the packet and charging mechanism with a rotating hopper and rotating discharging disks therefor, and a solenoid in the circuit for controlling the latter operated by the contact member.

27. In a packeting machine, the combination with means for forming and sealing the packet, of detecting means including an electrical circuit and a packet engaging member therein constructed and arranged to engage the packet to determine the presence of a complete packet, charging mechanism with a hopper, rotating discharging disk therefor carried by a lever provided with a roll, and a path therefor acting to control the movement of the disk and a solenoid in the circuit and a switch for changing the path of the roll and controlling the action of the disk.

28. In a packet forming machine, a heated plunger for manipulating the packet forming material, and plunger operating means comprising a plurality of sprockets, a chain running thereover and means for securing the chain to the plunger, to carry the packet down to the carrier, in combination with vertically swinging packet wall bending members actuated by the plunger.

29. A machine of the class described for closing the tops of containers comprising, in combination, a frame, with container transferring means, and progressively effective top edge indenting members, interlocking top pressing and laterally folding members, downwardly folding members, a fold bending member and a top flattening member, all cooperatively assembled therewith.

30. A machine of the class described for closing the tops of containers treated with a moisture repellent, dry adhesive, comprising, in combination, a frame with intermittently acting container receiving and carrying means, and progressively effective top edge indenting members; interlocking top pressing and laterally folding members; upwardly tucking, and swinging, crimping downwardly folding members; and fold base positioning and fold bending members; and container top flattening members, a plurality of which members are heated and act to make effective the dry adhesive and seal the container top, all cooperatively assembled.

31. A machine of the class described for closing the tops of containers treated with a moisture repellent, dry adhesive, comprising, in combination, a frame with intermittently acting means for transporting containers; container top progressively folding elements operative in sequence respectively including indenting members acting to indent the top edge of a container and hold it indented until the approach of the next folding element; interlocking members to press together and simultaneously laterally fold the top with a downwardly swinging movement of the members; a tucker acting to upwardly tuck the fold and a crimper to downwardly fold and crimp the laterally folded container top; a downwardly swinging lever to impart a lateral and downward bend to the folded top while hold-

ing the base of the folded top substantially in its original position and flattening the top of the container, all operatively assembled.

32. In a packeting machine, means for closing the top of the packet comprising movable suspended coacting members engaging the opposite walls of the packet top to impart an angular bend thereto at the top, operably adjacent thereto to hammer and anvil members to turn the bent packet walls downwardly, a flap crimping member, flap pressing jaws imparting an inclined bend thereto and positioning the same, and a flap tucking and a packet conveying member to tuck the folded packet top inwardly and press it downwardly while conveying the packet.

33. In a packeting machine, the combination with means for forming and sealing the packet, of detecting means including an electric circuit comprising an arm overlying the plane of travel of the packet, a plurality of movable arms thereon with contact members thereon constructed and arranged to move downwardly into the path of the packet at a predetermined time to determine the presence of a completed packet and to close a circuit if the packet is not present, and charging mechanism with a hopper and discharging disks therefor; and a solenoid in the circuit for controlling the same operated by the contact members.

34. In a packeting machine, the combination with means for feeding packet forming material, forming the packet with free side edges of the blank overlapping on the side walls of the packet, and means including vertically moving blades acting to turn the opposed blank edges at a sharp angle and cause one of them to overlie the other, charging and sealing the packet, including the formation of a horizontally crimped fold tucked laterally and pressed downwardly upon the packet top, of detecting means including a plurality of swingable packet contact members constructed and arranged to engage the packet under proper circumstances to determine the presence of a complete packet, charging mechanism including a hopper with charging measuring means, means for discharging the charge, and a charge leveller and elevator operated by the driving mechanism and acting to level the charge and elevate the surplus portion of the charge from the charge measuring means without crushing the charge material.

35. In a packeting machine, means to close the packet top comprising heated, angular interlocking members mounted above the packet to form an angular fold, hammer and anvil members, and a crimping member to press the fold together and crimp it.

36. In a packeting machine, means to close the packet top comprising heated, angular interlocking members mounted above the packet to form an angular fold, hammer and anvil members, a crimping member to press the fold together and crimp it, and fold pressing jaws to position the base of the fold centrally of the packet top and bend the positioned fold, and a fold tucker to heat and inwardly tuck the base of the fold preparatory to laying the fold flat on the packet top.
